UNITED STATES PATENT OFFICE.

BENJAMIN CHAPMAN CRANE, OF MONTESANO, WASHINGTON.

FIRE-HOSE NOZZLE.

SPECIFICATION forming part of Letters Patent No. 660,147, dated October 23, 1900.

Application filed December 27, 1899. Serial No. 741,743; (No model.)

To all whom it may concern:

Be it known that I, BENJAMIN CHAPMAN CRANE, a citizen of the United States, residing at Montesano, in the county of Chehalis 5 and State of Washington, have invented a new and useful Fire-Hose Nozzle, of which the following is a specification.

The invention relates to improvements in fire-hose nozzles.

10 The object of the present invention is to improve the construction of fire-hose nozzles, more especially that shown and described in Patent No. 626,596, granted to me June 6, 1899, and to provide a simple, inexpensive, 15 and efficient device adapted to be readily applied to a nozzle and capable of arresting the rotary motion of a stream of water and adapted also to serve as a guard or strainer to prevent anything from coming in contact with 20 the valves and clogging and interfering with the operation of the same.

The invention consists in the construction and novel combination and arrangement of parts hereinafter fully described, illustrated 25 in the accompanying drawings, and pointed out in the claims hereto appended.

In the drawings, Figure 1 is a longitudinal sectional view of a device constructed in accordance with this invention and shown applied to the nozzle illustrated in the said patent. Fig. 2 is a transverse sectional view. Fig. 3 is a longitudinal sectional view illustrating a slight modification of the device.

Like numerals of reference designate corresponding parts in all the figures of the drawings.

1 designates a tube arranged within a casing 2, constructed in accordance with the patent above referred to, and the said tube 1, 10 which is designed to be introduced into the said casing when the removable side thereof is detached, is provided at its inner or rear end with exterior screw-threads 3, which engage corresponding screw-threads 4 of the interior of the extension or neck 5 of the casing 2, as clearly illustrated in Fig. 1 of the accompanying drawings. The projecting portion or neck 5 is provided with interior screw-threads 6 for the attachment of a hose-pipe, 45 and the said screw-threads 4, which are smaller than the screw-threads 6, terminate short of the same to provide a shoulder 7, against

which the inner or rear end of the tube 1 abuts. Instead of providing the supplemental screw-threads 4 and introducing the tube into the 55 casing, as before explained, a tube 1^a may be employed, and, as illustrated in Fig. 3 of the accompanying drawings, this tube is provided at its inner end with an exterior enlargement having enlarged screw-threads 8, adapted to 60 engage the screw-threads 6 of the nozzle illustrated in Fig. 1 or the screw-threads of any other ordinary fire-hose nozzle.

Within the tube 1 are arranged longitudinal partitions 9, crossing each other at the longitudinal axis of the tube and disposed radially thereof to divide the said tube into quadrant-shaped passages, as clearly illustrated in Fig. 2 of the accompanying drawings. These partitions, which are adapted to arrest the rotary motion of a stream of water, are slightly tapered or wedge-shaped, their sides 10 being forwardly or outwardly converged to conform to the configuration of the tapered interior of the tube, whereby the said partitions are 75 wedged therein, and the outward pressure of the water will operate to hold them in place. Besides operating to counteract the rotary motion of the stream of water passing through the hose and nozzle the device also serves as 80 a guard or strainer attachment to hold in check anything which might clog and interfere with the operation of the valves. The partitions, which may be formed integral with each other or interlocked in any suitable manner, are readily removable from the tube when 85 the latter is detached from the casing of the nozzle.

It will be seen that the device, which is exceedingly simple and inexpensive in construction, is adapted to be readily applied to nozzles and that it is capable of arresting the rotary motion of a stream of water and of preventing the same from being broken up when it enters the cylindrical casing, whereby a 95 straight stream of increased power is caused to issue from the nozzle. It will also be apparent that besides operating to arrest this rotary motion of the water the device serves as a guard or strainer to prevent anything 100 from entering the casing which might clog or interfere with the operation of the valves.

What is claimed is—

1. The combination with a hose-nozzle pro-

vided with a cock or valve and having screw-
threads in rear of the same; of a detachable
device comprising a tube exteriorly threaded
to engage the said screw-threads and located
5 in rear of the cock or valve, and removable
partitions arranged within the tube, said par-
titions being adapted to arrest the rotary mo-
tion of a stream of water and forming a guard
or strainer to protect the cock or valve, sub-
10 stantially as described.

2. The combination of a hose-nozzle having
a valve and provided with interior screw-
threads and having a shoulder in rear of the
screw-threads, a tube exteriorly threaded to
15 engage the screw-threads and fitting against
the said shoulder, said tube being located in
rear of the valve, and partitions arranged
within the tubes, substantially as described.

3. The combination of a nozzle having a cock
or valve, a tube detachably secured within the 20
nozzle and located at a point in rear of the
cock or valve, said tube being provided with
a tapering interior; and the partitions having
tapered or converged edges and fitting within
the tube to arrest the rotary motion of a stream 25
of water and forming a guard or strainer to
prevent the valve or cock from becoming
clogged, substantially as described.

In testimony that I claim the foregoing as
my own I have hereto affixed my signature in 30
the presence of two witnesses.

BENJAMIN CHAPMAN CRANE.
